UNITED STATES PATENT OFFICE.

REGINALD A. FESSENDEN, OF BROOKLINE, MASSACHUSETTS.

APPARATUS FOR PHONOGRAPH-KINETOSCOPES.

1,213,176.

Specification of Letters Patent. Patented Jan. 23, 1917.

Application filed June 27, 1916. Serial No. 106,247.

To all whom it may concern:

Be it known that I, REGINALD A. FESSENDEN, of Brookline, in the county of Norfolk and State of Massachusetts, a citizen of the 5 United States, have invented a new and useful Improvement in Apparatus for Phonograph-Kinetoscopes, of which the following is a specification.

The methods and apparatus described 10 herein relate to the production and transmission of sound, and more particularly to the transmission of sound, and especially speech and music, to large audiences: and more particularly speech, in connection with 15 moving pictures and their visual display.

The drawing accompanying this specification shows diagrammatically apparatus for carrying out my invention.

In the figure, which is a diagrammatic 20 side elevation of the apparatus, 12 is an electromagnetic mechanism adapted to operate as a sound producer, and preferably an oscillator of the type used by me for submarine telegraphy and telephony, and described in Letters Patent of the United 25 States No. 1,167,366. 38 is a battery for furnishing current to the armature of the oscillator. 14 is a telephone transmitter and 13 is a switch. 11 is the diaphragm of 30 the oscillator arranged to act, also, as a moving-picture screen. In operation the moving pictures are thrown on the screen 11 in the usual manner, and preferably on the side opposite to that on which the oscillator 35 12 is attached. When it is desired to produce sounds in connection with the pictures, the switch 13 is closed and the operator talks into the transmitter 14, thereby setting the oscillator 12 in action and causing the screen 11, which serves as its diaphragm, to vibrate and throw the sounds 40 out toward the audience. In place of the telephone transmitter 14, any of the well-known equivalents may be used, such for example as the phonograph operated synchronously with the moving pictures, shown in

application for U. S. Patent Serial No. 685,699.

Heretofore in the practice of the art it has been customary, when sounds are to be 50 transmitted to a large audience, to use a horn. The speech so reproduced has not been clear and distinct, but masked by overtones, so that the words were practically indistinguishable, and, moreover, the sound is 55 unpleasantly loud close to the horn and weak at a distance from it. Moreover, when this method of transmitting sound has been used in connection with moving pictures, the source of sound is readily located and the 60 sounds do not appear to proceed from the mouths of the images of the actors thrown on the screen. The present invention, in which the diaphragm of the sound-producing mechanism occupies a large area (in 65 most moving-picture houses a large fraction of the cross-section of the hall), overcomes these disadvantages.

I have found by experiment that when the moving-picture screen is used to form the 70 diaphragm of the sound-producing mechanism, the sound does not fall off with the distance, but is of substantially the same intensity in all parts of the hall, i. e., that part of the audience at the back of the hall 75 hears the sounds, music or speech at substantially the same intensity and with the same clearness that those near the screen do. Also, that the illusion is produced that the sounds actually come from the mouths of 80 the images of the actors thrown on the screen.

What I claim as my invention is:—

1. A loud-speaking telephone having its diaphragm arranged as a kinetoscopic 85 screen.

2. Means for producing sound in an enclosure adapted to contain an audience, comprising a loud speaking telephone having a diaphragm of the same order of dimensions 90 as the cross section of said enclosure.

REGINALD A. FESSENDEN.
